UNITED STATES PATENT OFFICE

2,195,646

BOOK AND INDEX UNIT

George F. Green, Toronto, Ontario, Canada

Application September 14, 1938, Serial No. 229,859
In Canada September 4, 1937

4 Claims. (Cl. 283—38)

The principal objects of this invention are to provide a means for indexing books, particularly telephone and other directories, which may be readily placed in position between the pages of

5 the book to afford means for readily opening the book at the desired place and which will provide accommodation for the placing of selected names, addresses and numbers for rapid reference.

10 A further and important object is to provide a series of index members, the tabs of which projecting beyond the book leaves will overlap so that they will afford protection against damage through rough usage, and further to devise a tab which will not be readily damaged.

15 The principal features of the invention consist in the novel construction of strips of tough paper, metal or fabric having means at one end for securing same between the book leaves at or close 20 to the binding of the book and having at the other end a hinged index tab adapted to project beyond the book leaves and to be operable to spread the leaves apart to facilitate the entry of the finger between the leaves, said strip being 25 adapted to receive entries of selected addresses, names or numbers.

In the accompanying drawings

Figure 1 is a perspective view of an open book showing the application of my invention thereto.

30 Figure 2 is a perspective view of one of the index strips ready to be inserted in a book.

Figure 3 is a perspective detail of a modified form of index strip of doubled formation.

35 Figure 4 is a perspective detail of a further modified form of index strip.

Figure 5 is an enlarged perspective detail of a portion of a further modified form of index strip showing a modified means of fastening same in the book.

40 Figure 6 is an enlarged sectional elevational view of the bound back of a book illustrating the application of the strip shown in Figure 5.

Figure 7 is an enlarged perspective detail of 45 a portion of an index strip showing a further modification of means for fastening same in the binding.

Figure 8 is an enlarged elevational detail of a portion of the front edge of a book illustrating 50 the overlapping arrangement of the index members.

Figure 9 is a plan view of a portion of a book showing the arrangement of several overlapping index members.

55 Figure 10 is an enlarged elevational detail of

a portion of a book showing the application of the leaf lifting index tab.

Figure 11 is a view similar to Figure 10 showing a slightly modified form of lifting tab structure.

Figure 12 is a plan detail of an index strip of the form illustrated in Figure 10.

Figure 13 is a plan detail of an index strip as illustrated in Figure 11.

Figure 14 is a detail view showing the hinge joint of the index strip.

Telephone and other forms of directories and books are subject to constant use and much valuable time is wasted in locating the desired information due to the fact that such publications are not provided with any form of index means for readily locating the desired section. Such constant use results in the very rapid deterioration of the book which of course, aggravates the condition and results in increased loss of time with 20 much annoyance.

It is the purpose of this invention to provide means for effectively and economically indexing such books and as illustrated in the accompanying drawings.

As shown particularly in Figures 1 and 2 the index members 1 are formed of a strip of tough, comparatively stiff material having a gummed strip 2 on one side thereof at one end and the other end is doubled under and cemented to form 30 a reinforced tab 3. The strip is preferably formed with a score mark 4 extending thereacross along the inward edge of the tab which forms a "hinge" to permit the tab to bend readily so that the strip will not crack and its usefulness be impaired. A score mark 5 is also provided extending across 35 the strip adjacent to the gummed surface to permit the "hinging" of the strip at its inner end.

The surfaces of the index strip 1 are preferably 40 printed with spaced lines and columns to accommodate the entry of memoranda of names, addresses and numbers that may be required for ready reference under the index letter of the tab.

The top surface of each tab is preferably 45 printed in black with a white index letter at the lower edge and above the letter is a cross line 6 which serves the purpose of a guide in placing the index strips in a book, the line above the index letter being intended to register with the lower edge of the index strip arranged immediately thereafter.

The index strips as shown are preferably approximately an inch in width and as the tabs 3 50 are the full width of the strips when an alphabetical set of strips are placed in a book the tabs 55

overlap and if a book is dropped so that the index tabs are struck the tabs support each other from being broken off, as will be seen on reference to Figure 8.

5 In the slight modification shown in Figures 3 and 7 the index strips are doubled and the doubled end is secured to the book while the tab end projects beyond the outer end of the under portion. The reason for the doubled strip is to provide more space for the recording of special data on its surfaces.

10 In certain forms of books it may be found desirable to provide some mechanical means for securing the index strips and such a means is illustrated in Figures 5, 6 and 7 in which a thin metal strip 7, provided with pointed ends 8, is threaded through a slot 9 in the single strip 10 in Figure 5 or the slots 11 and 12 shown in the doubled over strip shown in Figure 7. These strips are fastened in the book by having the pointed ends 8 of the metal fasteners pushed through slots in the binding and the ends are bent over as shown in Figure 6 thereby holding the strip securely on a "hinge" connection.

15 In the form of the invention illustrated in Figure 4 the strip 13 is provided with lugs 14 projecting from one longitudinal edge and these lugs are gummed on one side to be fastened to the face of a page so that the strip may be turned over, hinging on the lugs so as to enable ready access to both faces of the recording surface.

20 It is an important feature to provide index members for books of the class described which upon being depressed will separate the pages to facilitate the insertion of the finger between the leaves in order to open the book and to further this object the index tabs may be formed as illustrated particularly in Figures 10 and 12 where a lug 15 extends rigidly inward from the hinged 25 portion of the tab so that when pressure is exerted to bend the tab downwardly the lug 15 presses upwardly lifting and separating the leaves above the index strip from the leaves below said strip.

25 In the form illustrated in Figures 11 and 13 a thin piece of metal or stiff card 16 may be secured in the double-over tab structure to serve the same purpose as the lug 15.

30 It will be understood that this index will be provided in an alphabetical set to be applied to a book and in placing same the Z index is inserted at the bottom of the first page of the Z entries in the book. The Y index strip is then inserted over the first page of the Y entries and with the 35 bottom edge overlying the index line arranged over the lower index letter. The remaining strips are arranged and located in a similar manner and when completed an extremely serviceable index is provided. Such an index may be readily

removed from a book, especially if a mechanical means for fastening the strips, such as is shown in Figures 5, 6 and 7, is used. It will of course, be apparent that indexed strips may be removed and replaced in another book by re-gumming the 5 fastening tab portions.

It will also be understood that it is desirable to have the maximum space available for special entries on the index strips but it is also desirable to keep the strips reasonably narrow so that they 10 will not cover an extensive area of the directory page and hence be objectionable as a hindrance to the rapid scanning of the directory page.

What I claim as my invention is:

1. A book index unit comprising in combination with a book, a flexible strip of tough fibrous material adapted to be secured between the leaves of the book and having an index tab hinged transversely of the strip at the outer end thereof, said tab having a rigid extension extending between the leaves of the book and adapted to lift the leaves on the tilting of the hinged index tab. 15

2. A book index unit comprising in combination with a book, a member adapted to be inserted between the leaves of the book and to be secured thereto and having the outer edge thereof doubled and being scored transversely at the inward side of the doubled portion to provide a flexible hinge joint, said doubled edge embracing a stiff member extending inwardly therefrom beyond the transverse score to engage between the leaves of the book and adapted on the pressure of the finger thereagainst to swing about the transverse score to lift the leaves above the index tab and form a recess for the insertion of the 30 finger tips to open the book. 35

3. A book index unit comprising the combination with a book, of a strip of material adapted for insertion between the leaves of the book, said strip having a substantially rigid index tab hingedly connected with the outer end, said tab and hinged connection being so constructed and arranged that by pressing transversely thereon the tab will swing on its hinge mounting relative to the strip to exert a separating lever-like force on the leaves, the face of said strip being adapted for the reception of quick reference data. 40

4. A book index unit comprising the combination with a book, of a strip of flexible material having one end arranged to be secured in the book adjacent the binding and having a reinforced tab hingedly connected with the outer end of the strip beyond the edge of the adjacent leaves and having a portion extending inwardly between the leaves adapted on the application of pressure thereto to swing on its hinge connection and exert a lever-like separating force on the leaves. 50 55
